VISIBLE INDEX DEVICE

Oliver K. King, Tenafly, N. J., assignor to Acme Visible Records, Inc., Crozet, Va., a corporation of Delaware

Application April 11, 1955, Serial No. 500,518

1 Claim. (Cl. 40—102)

This invention relates to improvements in index or record equipment of the class wherein flanged frames, panels or trays are adapted to receive flexible indicia strips.

More specifically, the present invention relates to directory units comprising a base or holder, generally adapted to be employed in a horizontal position, having pivotally mounted in vertically stacked relationship thereon a plurality of frames of the class indicated.

It is a particular object of the present invention to provide a unit of the class described wherein the respective frames are self-indexing, so that, as distinguished from prior devices, no separate tabs or indexing means for the respective frame contents are necessary.

Thus, in accordance with the present invention I provide a supporting stand comprising a pair of parallel upstanding walls adjacent one end of a supporting base and a plurality of frames pivotally engaged between said walls, the frames being adapted to replaceably receive flexible indicia strips disposed parallel to the hinge line. These frames are pivoted between the side walls in regularly spaced positions so that with respect to two adjacent frames, the upper one is rearwardly offset from the lower one a distance equal to that which will expose the last record or indicia strip on the front of the lower frame and thereby provide a self-indexing means for the frame contents. This permits listings to be added or otherwise changed without concern for label changing or other indexing detail, and provides a novel degree of flexibility for units of this class.

The objects and advantages of the present invention, and its details of construction and arrangement of parts, will be further apparent from a consideration of the following specification and accompanying drawings, wherein:

Fig. 1 is a plan view of the device of the present invention, and

Fig. 2 is a side elevational view thereof.

Fig. 3 is a perspective view of one of the frames removed from the holder.

Figs. 4, 5 and 6 are sectional views on the lines 4—4, 5—5 and 6—6, respectively, of Fig. 3.

Referring to the drawings, the reference numeral 10 indicates a supporting base, which if desired may include nonskid corrugated rubber support means 11, the unit being normally adapted to rest on a horizontal surface. Secured to and extending vertically from one end of base 10 are a spaced, parallel pair of side walls or brackets 12—12 integral with the rear end wall 13, the latter terminating at its upper end with an inturned inclined flange 14, the latter providing an abutment beyond the vertical for the frame members 15 when elevated for inspection of their contents, as shown by the dotted position in Fig. 2.

The side walls 12—12 are adapted to swingably receive and engage the frames 15 by hinge means such as the rods 16 secured within the bead 17 on the upper edge 70 of frame 15, the projecting ends of said rods being receivable in the apertures 19 formed in the upstanding

2

side walls 12. These apertures 19 are regularly spaced on an incline from adjacent the base 10 and forwardly of the rear wall 13, upwardly and rearwardly to adjacent rear wall 13 so that the adjacent panels can normally lie stacked in plane parallel relationship to each other and to the base 10 by virtue of the vertical spacing of apertures 19, and so that the last indicia strip 20 on the front of each frame 15 will be visible and unobscured by an upper adjacent frame by virtue of the horizontal spacing of apertures 19, which thus maintains the frames in regular longitudinally offset relationship to each other, as shown in Figs. 1 and 2.

The component frames 15 may be formed of a pair of plates 21—21 of equal extent, each having return-bent longitudinal edges to define the flanges 22—22 spaced from the surfaces of the plate for reception of the ends of an indicia or index strip 20, these strips conventionally being flexible so that they may be foreshortened and snapped into position, as shown in Fig. 3. In the illustration, the two plates 21—21 are joined back-to-back at one transverse end by means of the U-shaped strip or clamp 23 which closely grips the opposed faces of plates 21—21 and forms an abutment for the mounted strips 20.

At the opposed transverse end the plates 21—21 are clamped together by means of another U-shaped strip 24 which at the U-bend is formed as a bead 17 closely receiving and embracing the rod 16, the opposed legs of the strip being bent to lie flush with the plates 21—21 to further form abutments at the heads of the plates or composite frame for mounted strips 20.

As will be seen from Fig. 1, the frames, with the mounted strips 20 extending parallel to the hinge rod 16, when swingably mounted between the upstanding walls 12—12, are stepped or progressively offset from each other, so that when a frame is completely filled with strips 20, the last one, i. e., the one in abutment with strip 23 on the upper face of the frame, remains visible and provides a self-indexing means for the contents of the panel without requirement of tabs, label changing, or other indexing detail.

In a typical use the unit may comprise, for example, 7 or 13 frames, the strips 20 having typed thereon names followed by telephone numbers. These strips are arranged alphabetically on the frames, and such listing strips may be added or removed without concern for label changing or other indexing detail, the last one always providing a self-index for the frame contents, any vacant area above it on the frame being filled with blank strips providing an expansion factor until wanted for an actual listing.

In the illustrated construction, the rod 16 is fixedly secured in bead 17 and one of the laterally projecting ends is shorter than the other. The panels or frames 15 are yieldably urged against one of the brackets 12 by means of a resilient pad 25 secured to the opposed bracket 12 to retain the panels in yieldable, displaceable engagement, as more particularly described and claimed in the copending application of Walden E. Reed, Serial No. 500,368, filed April 11, 1955.

It will be understood that various changes may be made in the details of construction, such as that of the frame details, the means for hinging the frames to the upstanding wall and the details of the holder base construction, without departing from the spirit of my invention and its unique and time-saving self-indexing feature.

I claim:

In an index device, a base, spaced parallel side walls projecting from said base, a plurality of index panels each including an opposed pair of longitudinally extending flanges defining trough-shaped recesses for reception of the ends of flexible index strips and opposed transversely extending abutment members for limiting movement of

engaged index strips longitudinally of said panel, a plurality of index strips mounted on and filling the confines of said panel, said panels being normally disposed on said base in vertically-stacked plane-parallel stepped relationship exposing an engaged index strip lodged against the abutment member at one transverse end of the upper face of a panel free of concealment by the end of an upper adjacent panel, and laterally projecting rod means carried by the opposed transverse ends of said panels in pivotal engagement with said side walls retaining said panels in swingable engagement therewith.
